UNITED STATES PATENT OFFICE.

HENRY VAN HOEVENBERG, OF NORTH ELBA, NEW YORK.

GAS-BURNER CLEANER.

1,112,176.

Specification of Letters Patent. Patented Sept. 29, 1914.

Application filed April 7, 1913. Serial No. 759,383.

To all whom it may concern:

Be it known that I, HENRY VAN HOEVENBERG, a citizen of the United States, and a resident of North Elba, in the county of Essex and State of New York, have invented certain new and useful Improvements in Gas-Burner Cleaners, of which the following is a specification.

This invention relates to a gas burner cleaner and more especially to a type of use in connection with acetylene gas burners.

It is a well known fact that the outlet openings in acetylene burners are so very small that they become frequently clogged with small particles such as carbon, soot or dust and so shut off a portion of the gas or at least deflect the flame from its true course, so that the efficiency and illuminating power or brilliancy of the light is diminished. It is, therefore, necessary to clean out these pinhole openings from time to time. Inasmuch as these gas outlets are generally not greater than one-hundredth of an inch in size, great difficulty is found in inserting the cleaning point which must be as fine as a needle into the opening, especially if it is attempted in the dark, as when the flame becomes clogged in the evening and it is necessary to put out perhaps the sole light and remove the obstruction.

It is therefore an object of my invention to provide a burner cleaner which will readily guide a cleaning needle to a position in register with the pinhole outlet of a burner by coöperating with the burner itself. To accomplish this and further objects, advantage is taken of the form of most burners in having supplementary openings of graded magnitude leading to the pinhole outlet opening. The cleaning instrument is provided with a guide formed to fit snugly in these supplementary openings or sockets and thus bring the cleaning needle in accurate register with the pinhole opening itself. This guide, moreover, acts as a protector or guard for the slender cleaning needle itself, so that a further object is accomplished of having the delicate needle at no time exposed to danger of being bent or broken. That is to say, the guard and guide is floatingly mounted and normally held by a spring in a position covering and protecting the needle but capable of yielding on pressure so that the needle can pass out through an opening therein and through the pinhole gas opening.

The guard can be locked into protecting position so that the needle cannot be protruded. The guard can also be entirely detached for any purpose such as to replace the needle, clean the instrument itself, or replace any guide by another adapted to fit other styles of burners.

The cleaner is made in a handy form so that it can be readily manipulated and also so that it can be carried about in the pocket like a pencil. It is further made sectional, so that it can be minimized to a size small enough to be carried in a small vest-pocket.

Further features and advantages will be more fully described hereinafter and more particularly pointed out in the claims.

Referring to the drawings, Figure 1 is an enlarged view showing the device in use, with parts broken away to show the underlying structure. In this view, the cleaning needle, however, is shown in its retracted position just before it is projected through the guard to clean the pinhole aperture of the burner. Fig. 2 is a view similar to Fig. 1, with the exception that pressure has been applied to the instrument and thereby extruded the needle so that it has passed through the pinhole passage of the burner. Fig. 3 is a contracted assembled view of the device as a whole, showing it connected in position to carry about in the pocket as a pencil would be. Fig. 4 is an enlarged detail view partly in section showing the connection of the needle to the supporting or chuck rod. Fig. 5 is a detail view showing the relation of the guard and guide to the holder with the locking detent in apposition to the free-way groove so that the needle can be extruded from a position within the guard to a position outside the guard. Fig. 6 is a view similar to Fig. 5 with the exception that the locking detent has been moved over in position to the detaching groove, so that the guard can be bodily taken away from the holder. Fig. 7 is a view similar to Figs. 5 and 6, with the exception that the detent is shown in its locking position wherein the guard is prevented absolutely from being accidentally detached from the holder.

Referring more particularly to the separate parts of this invention as embodied in the form shown in the figures, 1 indicates an acetylene burner of the usual type in which opposed jets are directed to meet each other, so as to flare out or spread to form a

thin, wide flame. In such burners, there is usually provided a pin-hole passage or opening 2, through which a thin stream of the gas is projected from the main supply 5 passage 3 of the burner. The pinhole passage 2 forms an outlet and lets into a somewhat larger passage or socket 4, which in turn lets into a still larger passage or socket 5. These passages or sockets 4 and 5 may 10 be provided with suitable air holes 6^a to permit the air to come in and mix with the stream of gas as it passes from the burner into the air.

Advantage is taken of the peculiar shape 15 of the burner in guiding the instrument to a position such that it may be readily and properly operated. Concerning the details of the instrument, it includes a holder 6 which is shown in the form of a cylindrical 20 body opened at one end and provided with a socket 7 in which is seated a chuck or supporting rod 8. This rod 8 may be provided with a slot or socket 9 in which can be secured a slender cleaning needle 10 by any 25 suitable means as a cotter pin 11, which extends sidewise through the bar 8 and clamps the needle 10 in position by flexing it more or less to one side. Of course, if the needle is damaged or possibly burned out by using 30 the instrument when the flame is actually burning, it can be renewed by removing the cotter pin 11 and inserting a new one in place thereof. The needle 10 is not normally allowed to freely project in open 35 space as this would render it liable to be broken. Besides, it is desired to provide guiding means to direct the needle properly so that it will immediately enter the pin-hole gas outlet 2 when it is desired to use the 40 instrument. For this purpose, there is provided a combined guard and guide 12 which is shown cylindrical in form and of such magnitude to fit snugly within the holder 6, so that it can slide freely back and forth 45 in this holder. The guard 12 is provided with a central passage 13, so that during its sliding motion, it will allow for a relative movement between the chuck rod and itself, that is to say, the guard 12 can move within 50 the holder 6 and over the chuck rod 8. It is also essential that a passage 14 be provided for the needle 10, so that it may be extruded from the guard 12 when the guard is forced within the holder 6. This passage 14 55 is but little larger than the needle 10, so that it will form a supporting surface for the needle and guide it properly in its passage from the guard to the pinhole opening 2 and through the same. The guard 12 is normally held in its outer position and thus in 60 a covering or protecting position for the needle 10 by a spring 15 which is located between the end of the guard 12 and the bottom of the holder 6. This then forms a yielding support, so that the guard 12 may

be said to be floatingly mounted in the holder 6. The outer extremity of the guard 12 is so formed that it will coöperate with the sockets 4 and 5 of the burner to guide the instrument as a whole and more particularly the needle 10 to a position such that the needle 10 will extend in apposition to the pinhole opening 2. To accomplish this, the guard 12 is formed with a reduced nib 16 which almost exactly fits the socket 70 or opening 4 and is of sufficient length to bring the needle close up to the pinhole opening 2 when the guard is properly seated in the sockets 4 and 5. It will be noted that at least that portion of the guard 12 which 75 extends into the socket 5 is of an external diameter equal to the external diameter of the socket 5, so that it will snugly fit therein. The circular corners of the guard are slightly beveled away, so as to properly guide the 80 end of the guard into the sockets 4 and 5 until they are accurately seated therein. The guard 12 then not only forms a protecting covering for the needle 10, but also acts as guiding means to enable the instrument 85 to be properly located with respect to the burner and thus bring the needle 10 in direct apposition to the pinhole gas outlet 2, whereby the user need not fumble around in order to properly insert the needle 10 in 90 the act of cleaning. In order that the device may be conveniently handled, it may be desirable to have the same of considerable length say for example, the length of a pencil. For this purpose, there may be 100 fitted onto the holder 6, a union 18, which, however, is not so tightly fitted but that it can be forcibly removed. The union 18 may be reduced at both ends to enable an extension cap 19 to be fitted on in either one 105 of two positions.

In the position shown in Figs. 1 and 2, the extension cap 19 forms a handle so as to prolong the instrument, enabling it to be conveniently manipulated. This handle or 110 cover can also be used as a container for various sizes and shapes of guides or protectors, as it would not be possible to shape one guide that would fit every style of burner. In the position shown in Fig. 3, the 115 extension 19 is used as a cap or cover, shortening the device as a whole and enabling it to be readily inserted in the pocket. The intermediate large portion 20 of the union 18 may be knurled, so that it can be readily 120 held to enable the removal of the cap 19, and so that it itself can be removed from the holder 6. If it is desired, both the union 18 and the cap 19 may be entirely 125 detached from the holder, so that the device will be sufficiently small, so that it can be placed in a small vest-pocket. In such an event or in any case, it may be desired to prevent the extrusion of the needle when it is not desired to use the instrument. For 130

this purpose, a locking detent 20 is provided on the holder 6 and may be of any suitable form. This detent is arranged to extend in free-way grooves which permit 5 certain predetermined movements of the guard 12 and the holder 6 relative to each other. That is to say, when the detent 20 is in opposition to an operating groove 21, the guard and holder may have a relative 10 longitudinal movement such that the detent 20 passes into the groove 21, and so that the needle 10 is permitted to be extruded from the guard 12.

Communicating with the operating 15 groove 21, there is provided a locking groove 22 which extends circumferentially of the guard 12, so that the detent 22 can be forced over into the position shown in Fig. 7, such that the guard and holder cannot possibly 20 have a longitudinal movement relative to each other until they have had a rotary movement to bring the detent 22 to such a position that it will move in the operating groove 21 or in a detaching groove 23. This 25 latter groove communicates with the groove 22 and extends off the inner end of the guard 12, so that the guard can be readily detached from the holder 6 to enable the instrument to be cleaned or a new needle 30 inserted in the holder. There may be provided a slight ridge 24 between the detaching groove 23 and the operating groove 21 in the locking groove 22 so as to prevent the accidental disengagement of the guard 35 from the holder and requiring an actual forcing of the detent to a position in register with the detaching groove 23.

In using the device, the cap 19 is removed from the position shown in Fig. 3 and attached to the union in the positions shown in Figs. 1 and 2 to form an extension therefor. The guard and guide 12 is then inserted in the sockets 4 and 5 of the burner 1 until properly seated, when a slight pressure 45 is placed upon the device, so that the guard 12 remains stationary while the needle 10 proceeds farther until it has been extruded from the guard and passes through the pinhole gas passage 2, removing any 50 dirt or obstruction that may be found therein. When pressure is removed, the spring 55 will naturally cause the guard 12 to once more come out from within the holder 6, permitting the needle 10 to recede within the guard, protecting it from any danger of being bent or broken. The passage 14 of the guard is so small moreover, that it may act to clean the accumulative dirt from the needle as it recedes into the guard. It will 60 thus be seen that there is provided an extremely simple and efficient device which can be readily manipulated to clean a burner even in the dark and which is protected at all times from injury. It will 65 further be seen that the cleaner can be car-

ried in a more or less compact form so as to suit the convenience of the user.

While I have shown one embodiment of my invention, I do not wish to be limited to the specific details thereof, but desire to be protected in various changes, alterations and modifications which may come within the scope of the appended claims.

Having thus described my invention, I claim—

1. In a burner cleaner, the combination with a cleaning needle, of a holder for said needle, and a combined guard and guide for said needle acting to guide the needle to a position to be used and normally inclosing and covering said needle, said guard and said needle having a relative movement in the act of using said needle to permit the protruding of said needle during a cleaning operation.

2. In a burner cleaner, the combination with a cleaning needle, of a holder for said needle, and a guarding means for inclosing and protecting said needle at all times except when said needle protrudes while actually cleaning, said guard stopping by engagement with the burner being cleaned while said needle moves in through the outlet of the burner.

3. In a burner cleaner, the combination with a cleaning needle, of a holder for said needle, a guard for said needle, said guard and said holder having a relative movement, and a spring interposed between said guard and said holder normally holding said guard and said holder in such a position that said needle will be covered and protected by said guard.

4. In a burner cleaner, the combination with a cleaning needle, of a holder for said needle, a guard for said needle, said guard and said holder having a relative movement, a spring interposed between said guard and said holder normally holding said guard and said holder in such a position that said needle will be covered and protected by said guard, and a detent for preventing a relative movement between said guard and said holder.

5. In a burner cleaner, the combination with a cleaning needle, of a holder for said needle, a guard for said needle normally protecting said needle, and a detent for preventing a relative movement between said guard and said needle.

6. In a burner cleaner, the combination with a cleaning needle, of a holder for said needle, a guard for said needle, said guard having its front outer end formed to afford guiding means coöoperating with the internal passages of a burner to bring said needle in opposition to the pinhole gas outlet of said burner.

7. In a burner cleaner adapted to clean a burner having stepped passages or sockets

of varying magnitude, the combination with a cleaning needle, of a holder for said needle, and guiding means for said needle having a stepped end arranged to be inserted in said stepped sockets of said burner to determine the position of said needle with respect to said burner.

8. In a burner cleaner adapted to clean a burner having stepped passages or sockets of varying magnitude, the combination with a cleaning needle, of a holder for said needle, and guiding means for said needle having a stepped end arranged to be inserted in said stepped sockets of said burner to determine the position of said needle with respect to said burner, the corners of said steps upon said guiding means being beveled to permit the ready insertion of said guiding means into said sockets in said burner.

9. In a burner cleaner, the combination with a cleaning needle, of a chuck for supporting said needle, a guard for said needle having a passage to permit a relative movement between said chuck and said guard and also a passage to permit the extrusion of said needle from said guard, said passages fitting said chuck and said needle snugly.

10. In a burner cleaner, the combination with a cleaning needle, of a holder for said needle, a union detachably connected to said holder and being reduced at both ends, and a cap formed to snugly fit either end of said union so as to either form an extension for said holder or form a cover for said needle.

11. In a burner cleaner, the combination with a cleaning needle, of a holder for said needle, a guard for said needle, said guard having an operating groove and a locking groove, and a detent on said holder arranged to engage either one of said grooves to respectively permit a relative movement of said guard and said holder or lock said guard and said holder against relative movement.

12. In a burner cleaner, the combination with a cleaning needle, of a holder for said needle, a guard for said needle, said guard having a locking groove therein and a detaching groove therein, and a detent on said holder arranged to engage said locking groove or said detaching groove to respectively prevent said guard from being detached from said holder or permit said guard to be detached from said holder.

13. In a burner cleaner, the combination with a cleaning needle, of a holder for said needle, a guard for said needle, said guard having free-way grooves therein, and a detent on said holder engaging said grooves to determine the movement of said groove relative to said holder.

14. In a burner cleaner, the combination with a cleaning needle, of a holder for said cleaning needle, a chuck rod mounted in said holder and arranged to detachably support said needle, a guard for said needle slidingly mounted between said holder and said chuck rod, and a spring interposed between said guard and said holder normally maintaining said guard in a position covering said needle.

15. In a burner cleaner, the combination with a cleaning needle, of a holder for said cleaning needle, a chuck rod mounted in said holder and arranged to detachably support said needle, a guard for said needle slidingly mounted between said holder and said chuck rod, a spring interposed between said guard and said holder normally maintaining said guard in a position covering said needle, and a detent for determining the movements between said rod and said holder.

Signed at North Elba, in the county of Essex, and State of New York, this third day of April, 1913.

HENRY VAN HOEVENBERG.
